UNITED STATES PATENT OFFICE.

JOSEPH HODGSON, OF PHILADELPHIA, PENNSYLVANIA, ASSIGNOR TO THOMAS DOLAN, OF SAME PLACE.

DESIGN FOR SHAWL FABRIC.

Specification forming part of Design No. 5,783, dated April 16, 1872.

Specification describing a Design for a Shawl Fabric, produced or invented by JOSEPH HODGSON, of Philadelphia, Pennsylvania.

The nature of this design is represented in the accompanying drawings, in which the figure shows a portion of the shawl. The pattern consists of alternating stripes A and B, the portion B of the fabric being striped, and the stripe A being ornamented, as shown.

Without restricting myself to any specific colors, I claim as my invention—

The design for a shawl fabric, substantially as described and illustrated in and by the accompanying drawings.

In testimony whereof I have signed my name to this specification in the presence of two subscribing witnesses.

JOSEPH HODGSON.
